UNITED STATES PATENT OFFICE.

THOMAS J. HUBBELL, OF SANTA CLARA, CALIFORNIA, ASSIGNOR OF ONE-HALF TO WILLIAM H. WOLFE, OF SAME PLACE.

UNIVERSAL LADDER.

SPECIFICATION forming part of Letters Patent No. 416,622, dated December 3, 1889.

Application filed August 24, 1889. Serial No. 321,892. (No model.)

To all whom it may concern:

Be it known that I, THOMAS J. HUBBELL, of Santa Clara, Santa Clara county, State of California, have invented an Improvement 5 in Universal Ladders; and I hereby declare the following to be a full, clear, and exact description of the same.

My invention relates to a device which I term a "universal ladder," and it consists in 10 the combination of side bars with transverse steps hinged and jointed together at various points, so as to permit a considerable adjustment of the parts with relation to each other for various purposes, as hereinafter set forth 15 and claimed.

Referring to the accompanying drawings for a more complete explanation of my invention, Figure 1 is a view of my ladder, showing the parts in position suitable for fruit-picking or other similar purposes. Fig. 2 shows the parts in position to form the ladder and a scaffold or platform.

A A are two ladders, which may be made of any suitable length, having cross-bars or 25 steps B, as shown. At one end these ladders are provided with stout iron straps C, which are firmly secured to them, and, extending beyond the side bars of the ladder, they are bent so as to meet each other, and, holes being made through these straps, they are united 30 by the bolt D. Upon this bolt is also fitted a short section consisting of side bars E and the transverse bars or steps F, and to the opposite end of this short section is pivoted 35 another ladder consisting of side bars G and transverse bars H. The bolt I, which unites this section with the short section above described, passes approximately through the center of the sides G, and this latter section 40 is allowed to swivel or turn upon its bolt I, while the short section may also turn upon the bolt which unites it with the upper end of the ladder. This enables me to place the ladder with the two main sections united at 45 the top and with the foot or lower ends properly separated, the short section extending approximately horizontally from the top of the ladder. The section G H, which is connected to it by a bolt I, will stand with its 50 lower end upon either of the steps B of one

of the main side ladders and its upper end projecting to a considerable distance above and to one side of the main ladders. It will be manifest that this section G H may be caused to rest upon either of the steps of the 55 main ladder which is most convenient, and at the same time to one side thereof, the base formed by the two main ladders being sufficient to prevent its overturning. This arrangement makes the device extremely use- 60 fnl for fruit-picking, as the extension G H will enable the picker to reach the limbs of the trees at a considerable distance to one side of the main ladder, and when this side of the tree has been stripped, by simply turning the short section over upon the opposite side and reversing the section G H, so that the opposite end will rest upon the steps of the ladder upon the other side, an equal distance may be reached on that side of the 70 main ladder without moving it from its first position.

Across the base of the main ladders A B extends a section consisting of side bars K and transverse steps L. One end of this section 75 is attached to the base of one of the sections A B by a rod M, which passes through the two sections, and this rod serves as an axle for the wheels or rollers N, upon which the ladder may be easily trundled from one place 80 to another. The opposite end of the section K L is attached to the base of the ladder A upon that side by pins O, the ends of the section K L projecting sufficiently beyond the foot of the section A B to allow them to 85 be used for handles by which to wheel the ladder about.

When it is desired to employ the apparatus as a stage or platform, as for work upon the ceiling or walls of a room, the pins O are 90 withdrawn, so as to allow the section K L to be separated from the foot of one of the ladders A B. The two ladders A B are at the same time spread apart until they extend nearly at right angles with each other and the section K L is set up on end, so that the apparatus assumes the position shown in Fig. 2, one of the sections A B forming one side, the base K L the other, and the other section A B extending horizontally across the top of 95 100

the two, while the short section E F and the swiveled section G H extend out from one side of this frame-work, enabling the operator to climb to points not otherwise within reach. The portion A B, which is in a horizontal position, and the short extension which unites it with a swiveling section G H, forms a platform either with or without the use of covering-planks, and may be of sufficient height so that the operator can easily reach the ceiling or walls and upper portion of a room.

In order to hold the device in the position shown in Fig. 2, I have shown the latch-braces 15 R, one end of which is pivoted or fulcrumed to one of the sections and the other end having a hook-shaped notch, so that it may slide through a loop or staple S on the side of the horizontal section and engage with a pin, thus 20 holding the locking device firmly in position, as shown in Fig. 2. By releasing these latches the device may be turned to the position shown in Fig. 1 or folded up for transportation.

Having thus described my invention, what I 25 claim as new, and desire to secure by Letters Patent, is—

1. A ladder comprising the sections A B, hinged together at the top, a short section having one end pivoted to the top of the main sections, and a section G H, centrally 30 pivoted upon the end of this short section, substantially as described.

2. A ladder comprising the sections A B, united together at the top, a short section having one end pivoted to the top of the 35 main sections, and a swiveled section having its center pivoted to the end of this short section and having its opposite ends adapted to rest alternately upon the steps of the main sections A B, substantially as described. 40

3. A ladder composed of sections A B K L, a swiveled section G H, and the short uniting-section connecting it with the meeting ends of the sections A B, substantially as de- 45 scribed.

In witness whereof I have hereunto set my hand.

THOMAS J. HUBBELL.
